UNITED STATES PATENT OFFICE.

GEORGE RAAB, OF CLEVELAND, OHIO.

DESIGN FOR A QUILTING FABRIC.

SPECIFICATION forming part of Design No. 19,848, dated May 27, 1890.

Application filed April 17, 1890. Serial No. 348,427. Term of patent 3½ years.

To all whom it may concern:

Be it known that I, GEORGE RAAB, a citizen of the United States, residing at Cleveland, in the county of Cuyahoga and State of

Ohio, have invented and produced a new and original Design for Quilting Fabric, of which the following is a specification, reference being had to the accompanying drawing, forming a part thereof.

10 The figure is a diagrammatic plan.

My design consists of a quilted pattern representing a fuchsia-vine in a state of efflorescence and butterflies reveling among the flowers, or of a series of such figures if the

15 pattern be of large size; and the corner-pieces, to render them more full and beautiful, have on the inner side thereof a quilted figure rep-

resenting a bird in the attitude of flying. The fabric thus quilted presents a beautiful appearance, and is designed more especially 20 for lining for ladies' cloaks or other garments.

What I claim is—

The design for a pattern for quilting fabric herein shown and described, and consisting of quilted figures representing, respectively, 25 a flowering fuchsia-vine, butterflies, and a bird in the attitude of flying.

In testimony whereof I sign this specification, in the presence of two witnesses, this 31st day of March, 1890.

GEORGE RAAB.
